UNITED STATES PATENT OFFICE

145,638

DESIGN FOR A MAGNIFYING LENS

Myer Rosenberg, Chicago, Ill.

Application December 20, 1945, Serial No. 124,897

Term of patent 14 years

(Cl. D57—1)

To all whom it may concern:

Be it known that I, Myer Rosenberg, a citizen of the United States, residing at Chicago, in the county of Cook and State of Illinois, have invented a new, original, and ornamental Design for a Magnifying Lens, of which the following is a specification, reference being had to the accompanying drawing, forming a part thereof.

In the drawing:

Fig. 1 is a top perspective view of a magnifying lens showing my new design.

Figs. 2 and 3 are central transverse sectional views taken at right angles to each other; and

Fig. 4 is a bottom perspective view.

I claim:

The ornamental design for a magnifying lens, as shown.

MYER ROSENBERG.
